UNITED STATES PATENT OFFICE.

MORRIS MARCUS, OF CHICAGO, ILLINOIS.

SUSPENDERS.

SPECIFICATION forming part of Letters Patent No. 289,429, dated December 4, 1883.

Application filed October 23, 1883. (No model.)

To all whom it may concern:

Be it known that I, MORRIS MARCUS, a citizen of the United States, residing at Chicago, in the county of Cook and State of Illinois, have invented certain new and useful Improvements in Suspenders; and I hereby declare the following to be a full, clear, and exact description of the same.

My invention relates to an improvement in 10 the part of suspenders commonly called the "suspender-end," wherein the single strip of material forming each or both reaches between the body of the suspender and the button upon the body of the article of clothing to be sustained is doubled edgewise upon itself, and wherein the necessary button-hole is formed in each reach by uniting the two strands together at a desired point above its lower extremity.

15 Various devices have been invented for the purpose of securing durability of the button-holes provided in the suspender-end, and several have been patented.

Another patented device affords an attractive appearance to the article, but fails to effect the all-important requirement of durability of the button-hole.

The first-named improvements effect their purpose by the use of metallic attachments— 20 such as bands, tips, and the like—which surround or are secured to the material, while in the one last referred to, the button-hole being formed by crossing the strands at a certain point and securing them together by means of 25 stitches, durability of the said button-hole is lacking.

It is a peculiarity connected with the trade in the article of wearing-apparel in which it is desired to secure Letters Patent for my improvement that any metallic attachment arranged upon the suspender-end for the purpose of forming the button-holes and rendering them durable, even when such attachments are made ornamental to enhance the attractiveness of the appearance of the said suspender-end, is objectionable, for the reason, among others, that such attachments indicate a gaudy flimsiness, rendering them unsuitable for application to a better class of material, and, being liable to become detached or broken, they are undesirable.

It is my object to provide ends for suspenders that shall present an appearance to recommend them to the trade and to those who wear them, and in which the button-holes shall be 55 so formed that impairment thereof need only result from the actual wear upon the material of which they are formed; and to this end my invention consists in an improved securing device arranged at the desired point to form the 60 button-hole with the double parts, the said securing device comprising a strand or wire passed transversely through the interior of each of the layers of material, forming a reach, and extending out through the rear sides of 65 the same, the projecting ends being brought together toward each other and secured, whereby the means of securing shall be invisible when the front side of the suspender-end is presented to view, to provide on the said 70 front side a smooth and even surface.

Referring to the drawings, Figure 1 represents a suspender-end in elevation, showing the button-holes formed with my improved securing device, one reach being twisted to present to view the front side; and Fig. 2 is a sectional view, showing the manner of employing my securing device to effect the desired purpose.

A is a cap-piece, of leather or other suitable 30 material, which bears the ring B, and to which the material forming the reaches C is secured. These reaches may be formed of a single piece of material secured to the cap-piece A at a point to produce two hanging strands of the 35 desired relative length when such strand is doubled inward and edgewise upon itself, the ends thereof being also secured to the cap-piece; or the said reaches may be formed each of a separate piece of material doubled edgewise upon itself, and the ends secured to the 40 cap-piece A.

D is a wire or narrow metallic band, sharpened at both ends and caused to penetrate the material composing a reach at a point to form 45 a button-hole of the desired dimensions. The wire or band D passes transversely through each strand of the material, between the front and rear surfaces thereof, being inserted on the rear side near the edge of one strand and 50 caused to protrude near the opposite edge of the other strand, when the projecting ends are

bent over toward each other and secured by causing them to penetrate into the material, as shown at *k* in Fig. 2 of the drawings.

What I claim as new, and desire to secure by Letters Patent, is—

In a suspender-end made of suitable material bent double to form a reach, a securing device provided at a desired point to form a button-hole with the double parts, said securing device comprising a strand or wire passed

transversely through the interior of each of the double parts and extending out through the rear sides of the same, the projecting ends being brought toward each other and secured substantially as described.

MORRIS MARCUS.

In presence of—

CHARLES C. LINTHICUM,
DOUGLAS DYRENFORTH.
